TONE ARM CONTROL MECHANISM

Celin B. Dale, Oak Park, Ill., assignor to Webster-Chicago Corporation, Chicago, Ill., a corporation of Illinois

Application May 25, 1945, Serial No. 595,844

13 Claims. (Cl. 274—15)

1

During a number of years the time of many men has been devoted to inventing and designing automatic record changers for phonographs in an effort to make them thoroughly reliable, simple to manufacture, and to provide various special features.

The present invention is believed to provide a simplicity never before approached with equal dependability and performance characteristics and also to provide even greater dependability than that which has heretofore been considered excellent.

Another advantage of the present invention is the extreme ease with which the tone arm swings even when it is operating the mechanism which controls the starting of a record changing cycle. This would always be important from the standpoint of reducing wear on the records, but with the trend toward lighter pick-ups, it is increasingly important. As the pick-ups become extremely light, their ability to stay down in the sound groove to exert a lateral thrust becomes less. According to the present invention, the tone arm swings with such extreme ease that there is room for almost immeasurable improvement in reducing the weight of the pick-up. Of course, any reduction in the weight of the pick-up greatly reduces the wear on the records.

One of the features of the present invention which has greatly contributed toward the lightness of tone arm action is the reduction in size of the various cycle controlling parts and the balancing and mounting thereof in such a way that they may be moved with extreme ease.

One feature which contributes greatly toward the simplification of the apparatus is using a single lever for first raising a tone arm and then turning it. This involves a double-acting cam as well as a doubly pivoted lever so that the cam first tilts the lever about a horizontal axis to raise the tone arm and then swings it about a vertical axis to swing the tone arm. Another important contribution towards simplicity is in varying the set-down position of the tone arm between the correct positions for 10 or 12 inch records by simply shifting the bias of the cam follower or lever which swings the tone arm so that it is biased against an inside cam surface for one position and an outside cam surface for the other position.

It is easy to provide sufficient manufacturing accuracy so that the two different cam surfaces will space the two set-down positions the proper distance apart for the two record sizes. It is not practical, however, to position the parts with respect to one another with exact uniformity in successive machines. It is, therefore, necessary to adjust the tone arm position even though one adjustment may be made for both sizes of records at once. According to the present invention, however, the one necessary adjustment

2

is greatly facilitated by providing the means for this adjustment in the tone arm for the greatest accessibility and so that the operator can see the effect the adjustment makes.

5 According to another feature of the invention the feeding of two records at once is reliably prevented by a special and simple construction of the spindle which nevertheless permits the played records to be withdrawn readily without 10 removing the spindle. One form of this spindle will even permit the intermixing of ordinary records and records which are only half as thick as these records.

Additional objects and advantages of the invention will be apparent from the description and from the drawings; in which

feeding intermixed records of different thicknesses.

Although the law requires a full and exact description, such as that which follows, of at least one form of the invention, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

In the illustrated form the invention includes a platform 25 having a circular depression 27 within which is located a turntable 28 driven by friction drive wheel 30 which in turn is driven by a collar 31 on a motor 32. As seen in Fig. 3, the motor may be suspended below the platform 25. The motor and associated parts are preferably carried by a separate plate 33, as seen in Fig. 5, to permit their removal as an assembly. Drive wheel 30 is carried by a floating plate 34 which is spring urged in a direction to wedge the drive wheel 30 between collar 31 and the flange of turntable 28.

The turntable 28 rests on a gear and bearing member 35 (Fig. 13) which rotates about a stationary bushing 36 which projects upwardly from a bearing block 37, a bearing washer 38 preferably being interposed between the bearing block 37 and the thrust hub 39 of gear and bearing member 35.

Spindle

A stationary spindle 41 extends downwardly through bushing 36 and through a bottom plate 42 with which it has a non-circular interlock fit to prevent turning of the spindle. A cotter pin 43 normally prevents removal of the spindle 41. One of the advantages of the present invention is that records and even the turntable can be removed without removing the spindle, even though the spindle is provided with a latch which contributes to the thoroughly reliable sequential dropping of the records.

As seen in Fig. 13, the records yet to be dropped rest on a shoulder 46 of the spindle which preferably is curved to the shape shown. The edge of the lower record rests on one shelf 47 of an elongated pusher or push-off plate 48 at the lower edge of the slightly tilted records. If desired the records may be held against the shelf 47 by a conventional light pivoted weight not shown. The push-off plate 48 is moved inwardly so that a push-off shoulder 49 rising from the shelf 47 pushes the lower record R off of the spindle shoulder 46 so that the record drops down along the spindle, the pusher shelf 47 immediately being retracted out of the way. For dependability of feeding only one record, it is desirable that the second record R' be restrained against being moved with the bottom record R due to friction between the two.

According to the present invention, the record R' is reliably restrained by a latch 51 which, however, offers no material opposition to the upward movement of the records when they have been played. The latch 51 slides within a slot 52 in the spindle, being restrained and guided therein by a pin 53 which extends through a slot 54 in the latch 51. A record which bears against the side face 56 of the latch will be effectively restrained against lateral movement since no amount of lateral pressure against this

side face will displace the latch. However, in the case of lifting from the turntable the records which have been played, the upwardly moving record will strike the bottom face 57 of the latch 51 with the result that the latch will readily yield upwardly to the position shown in Fig. 15 so that the records may freely pass upwardly past the latch. The shaping of the slot is such as to serve as a cam to swing the latch to a position within the body of the spindle.

To prevent damage to the bottom record of a stack dropping onto the spindle shoulder 46, when a previous bottom record has just been released therefrom, resiliency is preferably provided in the path of transmitting the shock load. For this purpose, the spindle with its normal load is supported by spring 55, which yields upon the impact to allow the spindle to move downward slightly.

20 Intermixed records of different thicknesses

From Fig. 14, it will be seen that if records of only half the thickness of those shown were played, two records might slide under the latch 51. Of course if only such thin records were to be played, the latch 51 could be redesigned to extend down far enough to let only one thin record pass thereunder. If that were the case, however, the thick record would not get under the latch 51.

Sometimes it is very desirable to intermix thin and thick records. The spindle of Figs. 13 to 15 lends itself readily to solving this problem in a manner shown in Fig. 16. Here the latch 35 has been shaped with its lower face 57^a sloping so that a thick record will strike this lower face. The inclination of this face will enable the thick record to press the latch upwardly under the positive thrust of the push-off shoulder 49 far enough for the record to pass under the latch and be dropped onto the turntable. The inclined face 57^a will, nevertheless, offer enough added resistance to the movement of a record engaging it to restrain this record if it is not being directly pushed by the push-off shoulder 49. When the lower record R is a thin record, the second record R' may initially strike the latch 51 on its lower face 57^a but it will, nevertheless, be restrained by the latch 51. It will be understood that it does not take much force to restrain the second record R' because if there are several records on top of it so as to produce considerable friction between it and the bottom record R, these upper records will also produce friction on the upper surface of the second record R' helping to restrain it. To ensure sufficient resistance even when there are burrs or the like tending to slide the second record, a fine spring 60 may be provided urging the latch 51 downward.

The sloping position of the lower surface 57^a of the latch 51 during the play of the records should be such that neither a thick record nor the upper of two thin records will ever pass beneath it without striking it, and a bottom thick record will never strike above it on the nearly vertical surface 58^a. The height of the push-off shoulder 49 should be slightly less than the thickness of a thin record so that it will never strike the upper of two thin records.

Push-off post

The push-off head or plate 48 is part of a push-off post assembly seen best in Fig. 2. This post comprises a sleeve 61 mounted fast on a rod 62

which extends downwardly through a flange 63 and a base 64 of a bell crank lever 65. The push-off plate 48 is carried fast at the upper end of the post sleeve 61. As seen in Fig. 13, the bell crank lever 65 is pivoted by a pin 66 to a bracket 67 carried by the bottom plate 42; thus the entire push-off assembly is pivoted on the pin 66.

The assembly is urged toward the position shown in Fig. 13 by a spring 68. A cam follower roller 69 (Fig. 2) is carried at the end of bell crank lever 65 to engage a cam track 71 on main control cam preferably in the form of cam disk 72 which at the proper time pivots the push-off post assembly to push a record R off of the spindle shoulder 46 on the spindle.

To accommodate records of different diameter the elongated push-off plate 48 extends further from the sleeve 61 in one direction than the other and, when rotated with the sleeve 61, will present to the records either the push-off shoulder 49 at one end of the plate or a second push-off shoulder 49^a rising from the shelf 47^a at the opposite end of the plate. The plate 48 is held in the position to which it is turned by the force of a spring 73 through interaction of the sleeve 61 with a cam collar 74.

Drive of control cam disk

As previously indicated the turntable 28 is driven by the motor 32 and in turn drives gear 35 (Fig. 13). Gear 35 in turn meshes with pinion 76 which is fast on a shaft 77 to which a pinion 78 is also pinned. The pinion 78 meshes with a gear 79 which rotates freely on shaft or post 31. The gear 79 carries a driving disk 82 which at appropriate times is drivingly engaged with the control cam disk 72.

The driving engagement or clutching is accomplished by means of a clutch dog 83 which, as seen best in Fig. 8, is pivotally carried at 83^a by control cam disk 72 and is so balanced as to be biased toward the position shown in Fig. 8 in which the tip 84 of the dog 83 enters one of the notches 86 in the bottom of driving disk 82. The arrangement of these notches is seen best in Fig. 7.

The clutch member or dog 83 is normally restrained from assuming the position shown in Fig. 8 by the tip 87 (Fig. 4) of trigger or cycle control plate 88, seen best in Fig. 12.

The trigger 88 is pivoted on a post 89 and it is shaped with a downward extension 91 having a flange 92 thereon which, as seen in Fig. 3, is also pivoted to the post 89 and bears on an enlarged head or collar 93. Thus it is seen that the trigger 88 is pivoted at widely spaced points for stability. Furthermore, as will be seen from Figs. 3 and 4, it is approximately in static balance about the post 89 so that it will have little or no tendency to cant or tilt and cause any substantial friction on the side of the post.

Actuation of clutch dog

Since the driving disk 82 is rotating constantly, it follows that immediately upon removal of the trigger 88 from above the tip 84 of the dog 83, the tip 84 will enter a notch 86, thereby engaging the control cam disk 72 to the driving disk 82 so that the control cam disk starts to rotate. At the end of one revolution the dog 83 will pass under the tip 87 of trigger 88 which will tilt the dog back to the position shown in Fig. 3 so that the driving engagement through the dog 83 will be broken and the control cam disk 72 will cease rotating. Its position of rest will be determined

by the coaction between the cam follower roller 69 and a shallow depression 94, seen in Fig. 6. The control disk will remain stationary until the trigger 88 is again removed from dog 83.

5 The trigger 88 may be moved manually by operation of manual control lever 96 or automatically by tone arm 97.

Automatic operation

10 According to conventional practice, the record changing cycle is initiated at the end of the playing of one record by the more rapid swinging of the tone arm as a result of the special shaping of the needle track on the record. The tone arm

15 97 is mounted on a tone arm spindle 98 (Fig. 9) which rotates as the tone arm swings. Pivotedly mounted on the tone arm spindle 98 is a trip finger 99. This trip finger rests on the peripheral rim of a bushing 101 fast on the tone arm spindle 98 and is pressed against the bushing with a pre-determined pressure by a weak spring 102.

20 As the tone arm 97 approaches the end of the record, the trip finger 99 moves slowly against a trip lug 103 (Figs. 3 and 4) turned down from trigger 88. Continued movement of the tone arm pivots the trigger 88 slowly in a direction to swing its tip 87 from above the clutch dog 83. While the needle is in the playing portion of the needle groove of the record, however, the trigger 88 never completes the tripping movement, because it is frequently kicked back to its starting position by return lugs 104 on driving disk 82, which strike a return flange 106 turned up from trigger 88.

25 The spacing between the return lugs 104 is such that when the needle enters the steeper part of the needle groove after the playing portion of the groove, there will be time, with this increased speed of movement, for the trip finger 99 to swing the trigger 88 out from over the dog tip 84 of the dog 83 so as to release the dog to engage the driving disk 82.

Tone arm control

30 According to conventional practice, but in a novel manner, the tone arm spindle 98 is so connected to the tone arm that raising the spindle will raise the tone arm from the record, and rotating the spindle will swing the tone arm. According to the present invention, both of these movements are controlled by a single groove on the control cam disk 72. A disk 108 is rigidly carried by the tone arm spindle 98 and in fact may be integral with the bushing 101. The disk 108 is provided with a depending skirt 109 having in its lower edge a notch 111. A knife edge 112 carried by a lever 113 may be raised to engage the engagement surface on the bottom of the skirt 109 and raise the tone arm spindle 98 and hence the tone arm. The knife-edge 112 may be swung so that by friction or by engagement with notch 111 it will rotate the tone arm spindle 98, and hence, swing the tone arm. In order to

35 accomplish this two-way movement of the knife-edge 112, the lever 113 is doubly pivoted as seen best in Fig. 10. Pivoting about a horizontal axis is obtained by pin 114 which passes through the large flange 116 formed on lever 113 and through a bracket 117. The full height of the flange 116 bears against the smooth face of the bracket 117 for stability and a washer 118 may be positioned under the head of pin 114. If desired, the pin 114 may be in the form of a screw to facilitate a snug adjustment of the pivotal action of the lever 113, and the washer 118 may be

40 45 50 55 60 65 70 75 resilient if desired.

The bracket 117 is provided with upper and lower flanges 119 and 121 which are pivoted to a post 122, thus providing pivoting about a vertical axis.

The lever 113 carries a cam-follower pin 123 which is pressed by spring 124 against the under surface of control cam disk 72. The cam-follower 123 rides in a cam groove 126 of control disk 72. The base of this groove (the axially facing wall) is shaped to press the cam-follower 123 downwardly at the proper time, thus raising the knife-edge 112, which in turn raises the tone arm control unit or spindle unit (including disk 108 and spindle 98) to raise the tone arm.

When the tone arm has been raised, one of the side walls of the cam groove 126 cooperates with the cam-follower pin 123 to pivot the lever 113 about the post 122, thus swinging the knife-edge 112 which in turn swings the tone arm.

Control for different record sizes

After the tone arm is swung out from over the record which has been played and another record has been dropped thereon, the tone arm is swung into a position over the starting groove over the new record and is lowered to set the needle on the starting groove of the record. The set-down position is, of course, different for the different sizes of record. According to the present invention, the control for one set-down position or the other is provided in an exceptionally simple manner by pressing the cam-follower pin 123 against the outer wall of cam groove 126 for smaller records such as the common 10 inch records and pressing it against the inner wall of the cam groove 126 for large records such as the common 12 inch records. The lever 113 may be biased by leaf spring 127 to press the cam-follower pin 123 in either direction.

The direction of bias of the leaf spring 127 is controlled by turning the push-off post sleeve 61 as described under the heading "Push-off post." The rods 62 (Figs. 2 and 13) rotates with the push-off plate 48. Fast on the bottom of the rod 62 is the collar 131 carrying a crank arm 132. As seen best in Fig. 4, the crank arm 132 is linked to leaf spring 127 in any suitable manner as by wire link 133. The link should be so shaped as to be able either to push or pull the leaf spring 127. With the parts in position, as shown in Fig. 4, the link 133 would pull the spring 127 so as to press the cam-follower pin 123 against the inner wall of the cam groove 126. With the crank arm 132 turned in the opposite direction (by virtue of turning the push-off plate 48 for smaller records), the link 133 would pull the spring 127 so as to press the cam-follower pin 123 against the outer wall of cam groove 126.

The parts may be so constructed as to permit the turning of the push-off plate 48 in either direction from either position. In the illustrated form of the invention, however, it is normally limited to 180° movement by stops 136 (Figs. 1 and 3) carried by the platform 25 and positioned to engage a pin 131 carried by the sleeve 61.

Thus it is seen that when the record changing cycle starts, the base surface of the cam groove 126 pushes the cam-follower pin 123 downwardly to raise the knife-edge 112 and through it raise the tone arm. Thereafter a side wall of the cam groove 126 causes the cam-follower pin 123 to shift laterally thereby swinging the knife-edge 112 horizontally and thereby swinging the tone arm to the position out of the way of the record to be dropped. Then the cam-follower pin 123

5 following the same side wall of cam groove 126, will swing the knife-edge 112 in the opposite direction to move the tone arm 97 to the proper set-down position depending on the size of record being played, and for which the push-off plate 48 is adjusted.

Adjustment of set-down positions

The spacing between the two set-down positions is controlled quite accurately by the width of the cam groove 126 at the appropriate point and the diameter of the cam-follower pin 123. These parts can be formed quite accurately in manufacture so that the spacing between two set-down positions will be sufficiently accurate. However, it is not practical to make all the associated parts with such uniformity as to avoid all adjustment of the set-down tone arm position. With the spacing correct, one adjustment will take care of both positions.

According to the present invention this one adjustment can be made in the tone arm itself or at the head of the tone arm spindle so that the adjusting screw is readily accessible and the position of the tone arm can be observed while the adjustment is being made. The mounting of the tone arm which provides this adjustment is best seen in Figs. 9 and 11.

49 The tone arm spindle 98 carries fast thereon, at its top, a U-shaped bracket 141. To this bracket is pivoted an inverted U-shaped bracket 142. The legs of this bracket 142 are resilient to permit its removal from bracket 141, the pivots being stub pins carried by either bracket. The inverted bracket 142 has a hook 143 rigidly secured thereto, the upper portion of which forms a base plate 144. The tone arm 97 has a mounting plate 146 pivotally secured to the base plate 144 as by a rivet 147. The angular position of the mounting plate 146 on the base plate 144 is determined by an eccentric pin 148 which is eccentrically pivoted in base plate 144. The pin 148 is provided with a screw-driver slot to which access may be had through a hole 149 in the tone arm 97. Turning the pin 148 will simultaneously adjust both positions of the tone arm 97.

50 A cleat 151 is formed on plate 144 and extends through a slot 152, being turned down to bear against the upper surface of mounting plate 146 to hold the mounting plate firmly against base plate 144.

The mounting plate 146 is preferably mounted on the tone arm 97 by rubber grommets 154 to stop the transmission of vibrations.

55 A shield 156 is desirably provided for ornamental reasons and to protect the working parts from tampering.

A bracket 157 mounted on platform 25 extends into shield 156 and is positioned to be engaged by hook 143 when the tone arm spindle 98 is raised. This operates to tilt the tone arm 97.

When the tone arm swings in the raised position, the hook arm slides on the bracket 157.

56 When the needle is resting on the record, the hook 143 and the bracket 157 are out of contact. Hence the weight of the tone arm is carried by the needle and by the pivot pins 159 by which the inverted bracket 142 is pivoted to the bracket 151. The axis of these pivot pins preferably intersects the axis of the tone arm spindle 98. Thus the tone arm spindle has no lateral thrust exerted upon it by the weight of the tone arm when the record is being played. This makes possible a very simple and almost frictionless mounting of the tone arm spindle 98.

The tone arm spindle 98 is pivoted at its upper end directly at the platform 25 and at its lower end by a fixed stirrup or bracket 161 which is rigidly secured to the bottom plate 42. During the play of a record, the platform 25 and stirrup 161 merely serve as guides for the shaft 98, exerting substantially no thrust thereon.

At its lower end, the spindle 98 is conically shaped and its point rests on the bottom plate 42, the point forming a pivot and being very slightly rounded in accordance with good pivot practice. Since the load is carried entirely by the small pivot the frictional torque is extremely low.

Manual control lever

As seen best in Fig. 4, the manual control lever 96 is slidably and pivotally mounted on the underside of the platform 25 by means of a slot 163 in lever 96 through which a pin 164 extends. The outer end of the control lever 96 carries a knob 166 (Fig. 1) which projects upwardly through a T-shaped slot 167 on the platform 25. The T-shaped slot 167 permits moving the knob 166 in three directions from an intermediate point.

When the knob 166 is at the right hand end of the slot 167 as viewed in Fig. 1, the motor 32 is turned "off." Moving the knob toward the center of the slot starts the motor. This is accomplished by a switch control lug 168, which, when the switch is off, lies between the arms of a switch lever 169 forming part of switch 171. When the knob 166 is moved to the left from the right hand end of the slot 167, the lug 168 engages the right hand arm of switch lever 169 and actuates the switch to the "on" or closed position, thus starting the motor. When the knob 166 is moved to the right hand end of the slot 167, the lug 168 engages the left arm of the forked switch lever 169 and actuates the switch to the "off" position, stopping the motor.

Manual play

For the manual play of records it is desirable to prevent the actuation of the cycle starting mechanism. This is accomplished by moving the knob 166 inwardly into the center leg of the slot 167. In Fig. 4 the manual control lever 96 is shown in the position which it then assumes. Here it is seen that an arm 172 of control lever 96 engages an upturned lug 173 on the trigger 88 thus preventing this trigger from being moved to the cycle-starting position.

Manual cycle-starting

In the automatic play of records it is desirable to start the record changing cycle manually either for dropping the first record, or occasionally, for rejecting a record which has been started. This is accomplished by merely shifting the knob 166 to the extreme left in slot 167 and releasing it. The leftward shift brings a spring finger 174 which is carried by manual control lever 96 against the side of lug 173 on the trigger 88, thus actuating the trigger to the cycle-starting position. In other words it pivots the trigger 88 so as to draw the tip 87 thereof out from over the clutch dog 83, allowing the latter to engage the driving disk 82 to drive the control cam disk 72.

Further details

The bottom plate 42 is supported from the platform 25 by posts 81 and 89 previously mentioned and such additional posts 176 and 177 as may be desired.

The post 177 serves as a stop for limiting the

movement of the tone arm, this post extending through a notch in the disk 198.

The post 177 also serves as a stop for the movement of the trip finger 99, this trip finger being provided with a lug 178 which engages the post. The lug 178 is so positioned that it will normally strike post 177 before the tone arm reaches the end of its outward movement. This positions the trip finger 99 with respect to the tone arm so that it will come to bear on the lug 103 at the proper time.

The trip arm 99 preferably does not engage the lug 103 until near the end of the record. This leaves the tone arm moving with entire freedom during most of the play of the record. One of the advantages of the present invention is the almost frictionless nature of the tone arm movement. The friction is so slight that if the needle is rested on a smooth surface on the turntable, near the periphery thereof, the slight torque exerted thereby about the tone-arm spindle will cause the tone arm to swing inwardly, if the turntable is rotated forwardly, and outwardly, if the turntable is rotated rearwardly. However, even after the trip finger 99 strikes the lug 103, the friction is extremely low since the trigger 88 is so light and well balanced as to offer very little inertia or resistance. The slight thrust of the clutch dog 83 on the trigger is parallel to the axis of rotation of the trigger so that the thrust does not directly oppose movement of the trigger or necessitate compensating rotative forces. It has been found possible to have the trigger consistently yield with a side pressure exerted by the record groove of less than $\frac{1}{16}$ the side pressure required by the methods of control heretofore commonly used.

General operation

To play a series of records automatically, the records are slipped onto the spindle 41 and rested on the shoulder 46 thereof, the edge of the bottom record resting on the shelf 47 (or shelf 47a) of the push-off head 48. The control knob 166 is then shifted to the lefthand end of slot 162. This swings control lever 96 so that it trips the switch lever 169 to the "on" position to start the motor and moves spring finger 174 carried by the lever 96 against lug 173 of trigger 88, allowing clutch dog 83 to engage the main control cam disk 72 to the drive disk 82.

The control cam disk 72 tilts the lever 113 about a vertical axis and swings it about a horizontal axis to first raise and then swing the tone arm 97 and then lower it to the starting position on the record. In the meantime the first record to be played has been dropped onto the turntable by being pushed off of the spindle shoulder 46 by the push-off head 48 which was actuated by cam disk 72 operating on bell crank lever 65. The set-down position of the tone arm 97 is determined according to the setting of the push-off head 48 for large or small records. In one case the link 133 pushes the spring 127 so that the cam follower 123 bears on the outside wall of cam groove 126. Both cam walls are preferably shaped to start and stop the tone arm smoothly.

At the end of the record changing cycle the dog 83 glides under the trigger 88 which disengages it so that the record changing parts come to rest.

After approximately each revolution of the turntable one of the return lugs 184 presses the return finger 106 on trigger 88 and nudges it to the position shown in Fig. 4, in which position

it is restraining the clutch dog 83 from assuming its engaging position. However, when the playing of the record has been finished and the needle runs into the steep portion of the needle groove at the end of the record, the resulting increased inward speed of the tone arm will cause the trip finger 98 which at this time is bearing on the trip lug 103 of trigger 83, to move with sufficient speed to swing the trigger 83 out from over the clutch dog 83 between two notches by successive return lugs 104. The clutch dog 83 is immediately tilted by gravity to engage the drive disk 82 and drive the control cam disk 72 therewith, thus again starting the record-changing cycle of record-changing parts.

For manual play of a record, the records may be placed manually on the turntable and the control knob 166 may be moved to the central leg of the T slot 167, thus locking the restraining plate 88 in its restraining position so that the record-changing parts will not be actuated. The tone arm may then be placed on the record by hand.

To turn off the motor the control knob 166 is moved to the righthand end of slot 167. The tone arm is lifted from the record by hand. The record or records may be removed by simply lifting them off of the turntable since the latch 51, which prevents the dropping of more than one record at a time by the push-off head, offers no resistance to the removal of the records from the spindle.

Until the control knob 166 is moved to the end of the slot 167, the last record will be played over and over, but if desired, automatic shut-off means may be provided.

I claim:

1. Tone arm swinging means for record-changing apparatus and the like including a tone arm, means for mounting the same to permit the tone arm to swing vertically and horizontally, a cam having a single cam groove forming inner and outer walls, a follower in the groove, spring means to bias the follower optionally against the inner or outer wall by setting another part of the apparatus for large or small records, and means controlled by the follower for swinging the tone arm to the proper set-down position for large or small records.

2. Tone arm swinging means for record-changing apparatus and the like including a tone arm, means for mounting the same to permit the tone arm to swing vertically and horizontally, a cam having a single cam groove forming inner and outer walls, a follower in the groove, a spring connected to the follower, means connected to the spring and movable in opposite directions to cause the spring to bias the follower optionally against the inner or outer wall, and means controlled by the follower for swinging the tone arm to the proper set-down position for large or small records.

3. A tone arm control apparatus for automatic record changers and the like, including a tone arm spindle unit comprising a vertical spindle, a tone arm mounted on the spindle, means for mounting the spindle for vertical axial and horizontal rotative movements, a lever fulcrumed intermediately of its ends on approximately vertical and horizontal pivots at a point spaced from the spindle to form two arms, one arm being engageable with the tone arm spindle unit for raising and lowering the spindle and for rotating the same, a cam follower carried by the other arm of the lever, and a cam having cam surfaces arranged to engage the cam follower and positioned

for swinging the lever vertically and horizontally to impart said movements to the tone arm spindle.

4. A tone arm control apparatus for automatic record changers and the like, including a tone arm spindle unit comprising a vertical spindle and a tone arm pivoted to the spindle for vertical movement on a horizontal axis, means for mounting the spindle for vertical axial and horizontal rotative movements, a lever fulcrumed intermediately of its ends on approximately vertical and horizontal pivots at a point spaced from the said spindle to form two arms, one of the arms being engageable with the tone arm unit for raising and lowering the spindle and for rotating the same, a cam follower carried by the other arm of the lever, a cam having cam surfaces arranged to engage the cam follower and positioned for swinging the lever vertically and horizontally to impart said movements to the tone arm spindle, and means located in the path of the tone arm and engageable with the same for swinging the tone arm upwardly when the spindle is raised.

5. A tone arm control apparatus for automatic record changers and the like, including a tone arm spindle unit comprising a vertical spindle, a tone arm mounted on the spindle, means for mounting the spindle for vertical axial and horizontal rotative movements, a lever fulcrumed intermediately of its ends on approximately vertical and horizontal pivots at a point spaced from the spindle to form two arms, one of the arms being radially spaced from the spindle and having a portion engaging the tone arm spindle unit and movable to rotate the same and also for raising and lowering the spindle, a cam follower carried by the other arm of the lever, and a cam having surfaces arranged to engage the cam follower and positioned for swinging the lever vertically and horizontally to impart said movements to the tone arm spindle.

6. A tone arm control apparatus for automatic record changers and the like, including a tone arm spindle unit comprising a vertical spindle and a tone arm pivotally mounted on the spindle for vertical movement on a horizontal axis, means for mounting the spindle for axial and rotative movements, a lever fulcrumed intermediately of its ends on approximately vertical and horizontal pivots at a point spaced from the spindle to form two arms, one of the arms having a portion radially spaced from the spindle and engageable with the tone arm spindle unit for raising and lowering the spindle and for rotating the same, a cam follower carried by the other arm of the lever, a cam having cam surfaces arranged to engage the cam follower and positioned for swinging said lever vertically and horizontally to impart said movements to the tone arm spindle, and means located in the path of the tone arm and engageable with the same for swinging the tone arm upwardly on the spindle when the spindle is raised.

7. A tone arm control apparatus for automatic record changers and the like, including a tone arm spindle unit comprising a vertical spindle and a tone arm mounted on the spindle, means for mounting the spindle for axial and rotative movements, a lever fulcrumed intermediately of its ends on approximately vertical and horizontal pivots at a point spaced from the spindle to form two arms, one of the arms being engageable with the tone arm spindle unit and movable vertically and horizontally for raising and lowering the spindle and for rotating the same, a cam follower carried by the other arm of the lever, and a cam including a cam track consisting of

a single continuous groove receiving the cam follower and having inner and outer walls presenting cam surfaces for engaging the follower for swinging the lever horizontally in opposite directions, said cam track also including a bottom cam surface for engaging the cam follower for swinging the lever vertically to raise and lower the spindle.

8. A tone arm control apparatus for automatic record changers and the like, including a tone arm spindle unit comprising a vertical spindle and a tone arm mounted on the spindle, means for mounting the spindle for axial and rotative movements, a lever fulcrumed intermediately of its ends on approximately vertical and horizontal pivots at a point spaced from the spindle to form two arms, one of the arms being engageable with the tone arm spindle unit for raising and lowering the spindle and for rotating the same, a cam follower carried by the other arm of the lever, and a cam having a cam track consisting of a single continuous groove including variations in two transverse directions, the variations in one direction moving the cam follower and said lever in a direction to raise and lower the spindle and the other variations moving the cam follower and the lever in a direction to rotate the spindle for swinging the tone arm horizontally in opposite directions.

9. A tone arm control apparatus for automatic record changers and the like, including a tone arm spindle unit comprising a vertical spindle and a tone arm pivotally mounted on the spindle for vertical movement on a horizontal axis, means for mounting the spindle for axial and rotative movements, a lever fulcrumed intermediately of its ends on approximately vertical and horizontal pivots at a point spaced from the spindle to form two arms, one of the arms being engageable with the tone arm spindle unit for raising and lowering the spindle and for rotating the same, a cam follower carried by the other arm of the lever, a cam having a cam track consisting of a single continuous groove including variations in two transverse directions, the variations in one direction moving the cam follower and the lever in a direction to raise and lower the spindle and the other variations moving the cam follower and the lever in a direction to rotate the spindle and swing the tone arm horizontally in opposite directions, and means located in the path of the tone arm and engageable with the same for swinging the tone arm upwardly on the spindle when the spindle is raised.

10. A tone arm control apparatus for automatic record changers and the like, including a tone arm spindle unit comprising a vertical spindle and a tone arm mounted on the spindle, means for mounting the spindle for axial and rotative movements, a lever fulcrumed intermediately of its ends on approximately vertical and horizontal pivots at a point spaced from said spindle to form two arms, one of the arms being engageable with the tone arm spindle unit for raising and lowering the spindle and for rotating the same, a cam follower carried by the other arm of the lever, and a cam having cam surfaces arranged to engage the cam follower and positioned for imparting said movements to the lever.

11. A tone arm control apparatus for automatic record changers and the like, including a tone arm spindle unit comprising a vertical spindle and a tone arm mounted on the spindle, means for mounting the spindle for axial and rotative

movements, a horizontal disc mounted on the spindle and having a peripheral edge radially spaced from the spindle and provided with a notch, a lever fulcrumed intermediately of its ends on approximately vertical and horizontal pivots at a point spaced from said spindle to form two arms, one of the arms being engageable with the horizontal disc and with the notch thereof for raising and lowering the spindle and for rotating the same, a cam follower carried by the other arm of the lever, and a cam having cam faces arranged to engage the follower and positioned to impart to the lever said vertical and horizontal movements for actuating said disc.

15. 12. A tone arm control apparatus for automatic record changers and the like, including a tone arm spindle unit comprising a vertical spindle, and a tone arm mounted on the spindle, means for mounting the spindle for axial and rotative movements, a lever fulcrumed intermediately of its ends on approximately vertical and horizontal pivots at a point spaced from the spindle to form two arms, one of the arms being engageable with the tone arm spindle unit for raising and lowering the spindle and for rotating the same, a cam follower carried by the other arm of the lever, a cam having a single continuous cam groove receiving the follower and forming inner and outer walls provided with variations for moving the follower and for rotating the spindle and the lever for swinging the tone arm horizontally, said groove being also provided with a cam surface for engaging the follower to swing the lever vertically and raise and lower the spindle, and means to bias the follower optionally against the outer or inner wall of the cam groove for large or small records.

30 13. A tone arm control apparatus for automatic record changers and the like, including a tone arm spindle unit comprising a vertical spindle, a bracket pivoted to the spindle for swinging movement on a horizontal axis, a tone arm carried by the bracket and pivoted to the same for transverse pivotal adjustment with respect to the bracket, and an eccentric device mounted on the bracket and engaging the tone arm for adjusting the tone arm laterally with respect to the bracket and for securing the tone arm in its adjustment.
